UNITED STATES PATENT OFFICE.

SAMUEL MARCUS, OF BROOKLYN, AND ALEXANDER KONOFF, OF NEW YORK, N. Y.,
ASSIGNORS TO MARKON MANUFACTURING CO., INC., OF NEW YORK, N. Y., A COR-
PORATION OF NEW YORK.

ROLLING EYES FOR DOLLS.

Application filed August 31, 1927. Serial No. 216,530.

This invention relates to an improvement in doll eye sets, and particularly to eye sets of the so-called rolling type, that is eye sets in which the eyes are adapted not only to oscillate relatively into opened and closed positions but in which the eyes also roll from side to side when the doll is tilted one way or the other.

An object of the present invention is to provide an eye set of the type indicated and which is of simple and inexpensive construction while maintaining all of the essential features of adjustment enabling the eyes of the set to be brought into appropriate register with the eye openings of a doll head.

A further detailed object is to improve the arrangement of parts by which the eyes are supported, to the end that the eyes may be more accurately positioned within the sockets of the head notwithstanding inaccuracies in parts of the eye set.

A further detailed object is to provide simple and efficient means whereby the eyes may be easily connected in adjusted relationship upon their supporting cross rod.

A further detailed object is to so arrange the parts as to avoid necessity for objectionable cutting away of any part of the eye shells to facilitate the rolling movements of the eyes.

A further detailed object is to provide improved means facilitating a substantially universal adjustment of the iris carrying portions of the two eye shells with respect to each other.

A further detailed object is to provide an improved form and arrangement of gravity control device for the eyes.

Other objects and aims of the invention, more or less specific than those referred to above, will be in part obvious and in part pointed out in the course of the following description of the elements, combinations, arrangements of parts and applications of principles constituting the invention; and the scope of protection contemplated will be indicated in the appended claims.

In the accompanying drawings which are to be taken as a part of this specification, and

in which we have shown merely a preferred form of embodiment of the invention:—

Fig. 1 is a rear elevational view of an eye set constructed in accordance with this invention, the same being shown in association with a doll head illustrated in vertical section.

Fig. 2 is a horizontal sectional view taken substantially upon the plane of line II—II of Fig. 1.

Fig. 3 is a vertical sectional view taken substantially upon the plane of line III—III of Fig. 1.

Fig. 4 is an enlarged rear elevational view of one of the eyes shown in the preceding figures and illustrating a modified form thereof.

Fig. 5 is a transverse sectional view taken substantially upon the plane of line V—V of Fig. 4.

Fig. 6 is a transverse sectional view taken substantially upon the plane of line VI—VI of Fig. 4, and

Fig. 7 is a sectional view similar to that seen in Fig. 6 but illustrating a further modified construction of the eye shell.

Referring to the drawings for describing in detail the structure illustrated therein, the reference character L indicates a doll head or the like, the same being hollow and having the spaced eye sockets 1 and 2 at opposite sides of the central or nose portion 3, all as usual.

The reference character G indicates a suitable form of bracket or supporting member by means of which the eye set is intended to be connected with the inner surface of the head. This bracket or supporting member may take any desired form but is preferably of the general type as indicated in the pending application of Alexander Konoff, Serial No. 141,943, in that it consists of a body portion 4 which extends horizontally across the head at the rear of the two eye sockets and carries a pair of attaching members 5 and 6 slidable into and out of retaining engagement with the side walls of the head. A pair of arms as 7 and 8 extend forwardly from the body to rotatably support the cross rod H.

The arms 7 and 8 as herein illustrated are

spaced further apart than in the structure illustrated in the pending application referred to so as to engage the cross rod nearer to the centres of the respective eyes 9 and 10, being 5 preferably disposed to engage the cross rod within the hollows of the eyes so as thus to more directly and accurately support the individual eyes.

The cross rod H extends between the arms 10 7 and 8 and has its opposite end portions as 11 and 12 rotatably mounted within suitable bearing openings as 13 and 14 of the arms 7 and 8. The mid portion as 15 of the cross rod is offset backwardly toward the body 4 of 15 the supporting member so as to provide clearance as at the points 16 and 17 for the marginal edges of the eyes 9 and 10 and permit a suitable degree of rolling motion of said eyes without necessity for the side notches usually provided theretofore in eyes of this type for clearing the cross rod, it being noted that the end portions 11 and 12 are disposed in substantial axial alignment with each other and intersect the spherical centres of the eyes.

25 The eyes 9 and 10 are connected with the cross rod by means of connector members as 18 and 19 respectively. These are identical in the two eyes and a description of one will apply to both, viz: An elongated piece of material, preferably metal, having a central circular opening as 20 through which the cross rod extends, and the material being provided with slits as 21 and 22 extending longitudinally thereof communicating with the opening 20 at opposite sides. The slits at their outer ends terminate short of the ends of the piece of material, and the opening 20 is normally of slightly less diameter than the diameter of the cross rod so that when the cross rod is 40 forced into the opening the two halves as 23 and 24 of the member at opposite sides of the slits are sprung or bowed apart by the forced entry of the cross rod and thereafter continue to exert a strong frictional grip upon the cross rod. The material from which this member is made is of course of a suitably springy character to permit the bowing of the halves 23 and 24 and to generate the spring grip mentioned.

45 50 In order to facilitate the forced entry of the cross rod into the opening 20 the end of the cross rod is preferably tapered to a cone-shape as at 25.

The connector member is thus made to have 55 a firm frictional grip upon the cross rod of a character which while efficiently retaining the connector member in any position to which it is forced will nevertheless permit ready manual adjustment of the connector member either rotatably about the cross rod or slidably along the length of the cross rod.

The structure of the connector member as thus far described is similar to that shown and described in the application of Samuel 60 65 Marcus, Serial No. 215,566.

At its upper and lower ends the connector member is formed with pivot extensions as 26 and 27 by which the eye is mounted, and intermediate its ends there is provided a bendable extension 28 serving as a stop to limit 70 the rolling movement of the eyes.

As suggested in Figs. 1 to 3 the eyes may consist each of an inner shell as 29 and an outer shell as 30. The inner shell may be of appropriate material such as sheet metal bent 75 into semispherical contour, and the outer shell may be of suitable material such as celluloid or the like formed of semispherical contour fitting closely about the outer surface of the inner shell. The outer shell would of course 80 contain the pictorial representation of an iris in the usual manner.

The inner shell may be provided with diametrically opposite bearing openings 31 and 32 fitting upon the pivot extensions 26 and 27 of the connector member so that the inner shell is pivotally connected with said connector member on a substantially vertical axis transversely of the cross rod to facilitate the so-called rolling movement of the eye, and 90 it may have a pair of stops as 33 and 34 struck inwardly thereof at suitable points for co-operating with the stop 28 in limiting the rolling movement of the eye, it being here noted that by adjustably bending the stop 28 to one side or the other the opposite limits of 95 rolling motion are adjustably determined, the adjustment being effected simply by forcefully pressing one or the other of the stops 33 or 34 against the stop 28 until the desired extent of bending movement has been accomplished.

The outer shell 30 may also have bearing openings as 35 and 36 therethrough, mating 105 bearings 31 and 32 of the inner shell for receiving the pivot portions 26 and 27 of the connector member whereby to hold the outer shell positively connected in position while at the same time permitting such adjustment of the outer shell rotatively upon the pivots 110 26 and 27 as may be desired, there being of course sufficient frictional contact between the two shells at all times to prevent any movement of the outer shell relative to the inner shell except when positive adjusting 115 force is applied by an operator.

Both the inner and outer shells are of suitably flexible material to permit them to be manually distorted to an extent sufficient to enable the extensions 26-27 to be snapped into the bearing openings 31, 32, 35 and 36.

The inner shell has connected therewith, preferably as an integral extension from its lower marginal edge, a weight carrying arm as 37. These arms, from the two eyes, continue downwardly and inwardly and are suitably connected together and weighted at their lower ends.

In the instance illustrated the arms are inclined toward each other and have bearing 130

openings as 38 at their lower ends within which engage pivot extensions as 39 from opposite sides of a centrally disposed weight 40. The weight 40 as illustrated consists simply of a piece of sheet material of suitable heft folded upon itself to provide a pair of jaws as 41 and 42 between which is gripped a short horizontally disposed length of wire the opposite ends of which continue beyond the opposite sides of the weight and are bent to provide the necessary pivotal connection for the pivot bearings 38.

At a suitable point in each arm 37, preferably near to the eyes, said arms are cut away as at 43—43 so as to reduce the strength of the arms in that particular locality and thus facilitate a localized and relatively easy point of bend for said arms by reason of which the eyes may be manually rotatably adjusted with respect to each other upon their vertical pivots, as well as upon the cross rod.

Fixed to the cross rod H, preferably at a point midway in its length, is a pair of bumper arms as 44 and 45 one extending below the cross rod adapted for engaging a surface portion as 46 of the doll head to limit opening movement of the eyes and the other extending above the cross rod adapted for engaging a surface portion as 47 of the doll head to limit closing movement of the eyes. These two bumper arms may consist of a single length of spring wire rigidly connected intermediate its length with the cross rod, as by welding, the portions of the wire extending above and below the cross rod thus affording spring bumpers as indicated.

From the above it will be understood that whenever the doll is moved from an upright to a reclining position the weight 40, controlled by gravity, will move relatively to cause the eyes, with the cross rod, to rotate within the bearing openings of the supporting arms 7 and 8 between open and closed positions, while either simultaneous or independent sidewise tilting of the doll will cause the weight to move relatively from side to side and produce an oscillatory or "rolling" movement of the eyes upon the pivot extensions 26—27 of the connector members 18 and 19.

If for any reason, when assembling the eye set with the doll head, it is desired to rotatably adjust the eyes independently of each other upon the pivots 26—27 this may be readily accomplished by either or both shifting the outer eye shell 30 about the inner eye shell 29 or bending one or both of the arms 37 at the weakened points 43, it being pointed out that in the former instance the adjustment is independent of the position of the stops 28, 33 and 34 while in the latter instance the adjustment is tempered by the position of said stops one of which, as 28, is bendable, as above described, for nicety of adjustment.

The eyes may also be adjustably moved relatively to each other either rotatably or longitudinally of the cross rod as fully set forth, and the bending of the arms 37 at the weakened points 43 may facilitate these adjustments if found necessary.

The arms 37, besides being bendable to facilitate adjustment of the eyes as heretofore referred to, are also bendable, at the weakened points 43, or elsewhere, forwardly or backwardly to dispose the weight 40 at the most desirable and efficient locality with respect to the vertical plane of the axial centre of the cross rod, as will be readily understood.

In the structure illustrated in Figs. 4, 5 and 6, it is suggested that if desired the inner shell as 48 of the eye may be provided with suitable slits or the like as 49—49 to form an appropriate number of spring fingers 50—50 collectively defining the necessary semispherical base or support for the outer shell 30. The outer shell will of course serve to hold all of the spring fingers in their correct semispherical positions while, inversely, the fingers will provide a smooth and uniform frictional grip against the inner surface of the outer shell sufficient to hold the outer shell connected against possibility of accidental displacement while at the same time rendering the outer shell universally adjustable about the inner shell.

In this instance the pivot extensions as 51 and 52 of the connector members 18 and 19 have no direct connection with the outer shell, the inner shell being preferably formed with relatively inset parts as 53 and 54 which are provided with bearing openings 55 and 56 to receive the pivot extensions 51 and 52.

The weight carrying arm as 57 is shown as continuing from the inset part 54 of the inner shell and as being thus spaced inwardly from the lower edge of the outer shell as at 58 a sufficient distance to provide a desirable amount of adjusting movement of the two shells with respect to each other without necessity for cutting away any part of the outer shell to accommodate the weight arm.

It will be understood of course that the inner shell is normally of a slightly greater diameter than the inner surface of the outer shell and that the application of the outer shell onto the inner shell will produce such a crowding of the spring fingers comprised in the inner shell as to generate the frictional grip necessary to retain the two shells adjustably connected together. Each of the shells is slightly more than half a sphere so as to avoid tendency for the outer shell to be discharged from its enveloping position.

In this structure it is suggested also that the cross rod may if desired be provided with a return bend as 59 disposing the central portion of the cross rod in the same axial plane as the end portions of said rod. By this arrangement the rod may be supported by its

mid portion if desired, in a bracket such for instance as that indicated in the copending application Serial No. 141,943 above mentioned, while yet affording ample clearance 5 as at 60 for the rolling movement of the eye.

By the structure shown in these figures it will be apparent that the iris carrying portion of the eye, in addition to having the various features of adjustment longitudinally 10 of the cross rod, rotatably of the cross rod and rotatably of the pivot extensions 26 and 27 of the connector members, as in the previous figures, is also, by reason of its universal mounting upon the inner shell, capable of equally 15 easy adjustment about a horizontal axis transversely of the cross rod, which latter adjustment is of considerable importance particularly in instances where eye lashes are connected with the outer shells and must be 20 brought into proper operating register and alignment with the eye openings of the doll head.

In the structure illustrated in Fig. 7 it is suggested that the inner shell as 61 may be of 25 the same construction as the inner shell 48 of Figs. 4 to 6 and that the outer shell as 62, instead of fitting directly to the inner shell, may be fitted about an intermediate shell as 63, being either rigidly connected with said 30 intermediate shell or frictionally adjustable thereabout as may be preferred, and the intermediate shell in turn being fitted about the inner shell 61 and having bearing apertures as 64 and 65 mating the bearing apertures 55 35 and 56 of the inner shell and pivotally engaging the extensions 51 and 52 of the connector member.

By this arrangement it will be seen that both the inner shell and the intermediate 40 shell are positively pivotally connected with the connector member somewhat after the manner suggested in the structure Figs. 1 to 3, these two shells having such frictional engagement with each other as to prevent their 45 unintentional movement with respect to each other but yet enabling an adjusting movement of the shells with respect to each other about the pivots 51 and 52. In instances where the outer shell 62 is rigidly connected 50 with the intermediate shell the outer shell will of course have no adjusting movement about a horizontal axis transversely of the cross rod as in the structure Figs. 4 to 6, but such an adjusting movement is however provided for in instances where the outer shell is 55 either universally adjustable about the intermediate shell or rotatably connected with the intermediate shell as for example if the outer shell be formed with an inturned flange as 60 66 at its rear edge overlapping the rear edge of the intermediate shell and thus preventing any movement of the outer and intermediate shells except a rotary movement which is 65 upon a horizontal axis transversely of the cross rod.

As many changes could be made in this construction without departing from the scope of the invention as defined in the following claims, it is intended that all matter contained in the above description, or shown 70 in the accompanying drawings, shall be interpreted as illustrative only and not in a limiting sense.

Having thus described our invention, what we claim as new and desire to secure by Let- 75 ters Patent is:—

1. In an eye set, a connector member by which to connect an eye to its supporting member, said connector member comprising an elongated piece of springy material having 80 an opening formed therethrough at one point in its length intended to receive the supporting member forced thereinto, said piece of springy material being formed with a slit extending longitudinally thereof communicating with said opening whereby to render opposite wall parts of the opening resilient with respect to each other to thus provide a spring grip of said wall parts upon said supporting member to thus enable manual 90 adjustment of the connector member upon the supporting member, and pivot parts provided upon the connector member by which to pivotally connect the eye thereto.

2. In an eye set, a pair of semispherical eye shells, a supporting member extending between said eye shells, connector members for connecting the eye shells respectively to the supporting member, said connector members each comprising springy parts providing a spring grip of the connector member upon the supporting member allowing manual adjustment of the connector member rotatably and longitudinally of the supporting member, each connector member having pivot 105 parts by which the respective eye shells are pivotally connected thereto, and each connector member and its respective eye shell having parts co-operative to limit pivotal movement of the eye shells upon said pivot 110 parts, said co-operative parts comprising spaced stops provided upon the eye shell and an extension of the connector member disposed intermediate said stops and said extension being manually bendable to facilitate 115 adjustment of the limits of the pivotal movement of the eye shell.

3. In an eye set, a pair of semispherical eye shells, a supporting member extending between said eye shells, connector members one for connecting the eyeshells respectively to the supporting member, said connector members each comprising springy parts providing a spring grip of the connector member upon the supporting member allowing manual ad- 120 justment of the connector member rotatably and longitudinally of the supporting mem- 125 ber, each connector member having pivot parts by which the respective eye shells are pivotally connected thereto, at least one con- 130

5 nector member having an adjustable extension protruding therefrom, and the adjacent eye shell having parts co-operative with said extension to thereby adjustably limit the pivotal movement of the eye shell upon said pivot parts.

4. An eye set comprising a supporting carrier having parts by which to rigidly connect it with a doll head, a pair of eye shells spaced apart, a supporting cross rod extending between said eye shells, bearing parts provided upon the supporting carrier spaced apart and pivotally engaging the cross rod one within the hollow of each eye shell, a stop member 10 fixed to the cross rod intermediate the eye shells adapted to engage parts of the doll head for limiting pivotal movement of the cross rod in said bearing parts, connector members one for each eye shell having pivotal 15 connection with the eye shells respectively providing easy pivotal movement of the eyes upon vertical axes transversely of the cross rod, and said connector members having spring parts arranged to provide a spring 20 grip of the connector members upon the cross rod insuring pivotal movement of the eye shells with the cross rod and permitting manual rotary and sliding adjustment of the eye shells upon the cross rod, together with 25 gravity acting means by which to cause pivotal movement of the cross rod and eyes in the bearing parts of the supporting carrier.
5. In an eye set comprising a pair of hollow eye shells spaced apart, a cross rod extending 30 between said eye shells, means engaging the cross rod within the hollows of said eye shells by which said eye shells are pivotally connected with the cross rod to swing upon vertical axes transversely of the cross rod, and gravity means for controlling movements 35 of the eye shells, the combination therewith of a supporting carrier having means by which to connect it with a doll head and having bearing parts extending there- 40 from into the hollows of the eye shells respectively for there engaging the cross rod to pivotally support the cross rod.
6. In an eye set comprising a pair of hollow eye shells spaced apart, a cross rod ex- 45 tending between said eye shells, means engag- 50 ing the cross rod within the hollows of said eye shells by which said eye shells are pivotally connected with the cross rod to swing upon vertical axes transversely of the 55 cross rod, and gravity means for controlling movements of the eye shells, the combination therewith of a supporting carrier consisting of an elongated body arranged rearwardly of the cross rod and extending substantially 60 parallel therewith, means at the opposite ends of said body adapted to engage portions of the doll head adjacent the eye shells respectively to thereby fix the body to the doll head, arms provided upon the body projecting forward- 65 ly from adjacent the opposite ends thereof,

said arms having bearing openings there- through disposed within the hollows of the respective eye shells and there receiving the opposite end portions of the cross rod to pivotally support the cross rod for oscillatory 70 movement upon a horizontal axis.

7. In an eye set, the combination of a pair of eye shells spaced apart, connector mem- 75 bers by which said eye shells are pivotally mounted to swing upon vertical axes, a cross 80 rod extending between the eye shells being connected therewith by means of said connector members and having an off-set part to provide clearance for the mentioned pivotal movement of the eye shells, a common sup- 85 porting carrier having parts by which it is fixed to the doll's head and other parts engag- 90 ing the cross rod within the eye shells to pro- 95 vide pivotal mounting for the cross rod where- by the cross rod is oscillatable upon a horizon- 100 tal axis intersecting the spherical centres of the eye shells, and gravity means for actuating the eye shells.

8. In an eye set, the combination of a pair of eye shells spaced apart, connector members 95 by which said eye shells are pivotally mounted to swing upon vertical axes, a cross rod extending between the eye shells being connected therewith by means of said connector members and having an off-set part to provide 105 clearance for the mentioned pivotal movement of the eye shells, the connector members hav- 110 ing frictional engagement with the cross rod whereby the eye shells are rotatably and slid- 100 ably adjustable upon the cross rod, a common sup- 105 porting carrier having parts by which it is fixed to the doll's head and other parts engag- 110 ing the cross rod within the eye shells to pro- 115 vide pivotal mounting for the cross rod where- by the cross rod is oscillatable upon a 120 horizontal axis intersecting the spherical cen- 125 tres of the eye shells, and gravity means for actuating the eye shells.

9. In an eye set comprising a pair of eye shells spaced apart, and gravity control means 110 for said eye shells, the combination therewith of a cross rod extending between said eye shells, said cross rod having opposite end por- 115 tions disposed in axial alignment and intersecting the spherical centres of the eye shells, connector members mounted upon said aligned end portions by which the eye shells are pivotally connected with said end por- 120 tions to swing upon vertical axes transverse to the length of the cross rod, means engaging said aligned end portions by which to pivot- 125 ally support the cross rod to swing upon a horizontal axis, portions of the cross rod ad- jacent said aligned end portions being off-set to provide clearance for the first mentioned pivotal swinging of the eye shells, and stops provided upon said off-set part of the cross rod to limit the horizontal swinging of the cross rod.

10. A cross rod for eye sets, said cross rod 130

comprising a length of wire having opposite end portions disposed in alignment adapted to intersect the spherical centres of the two eyes of an eye set and to have connector members mounted thereon by which the eyes may be pivotally connected therewith to swing upon vertical axes transverse to the length of the cross rod, said aligned end portions providing also parts to engage within pivot bearings by which the cross rod may be pivotally supported to swing upon a horizontal axis, and the portion of the cross rod intermediate said aligned end portions being off-set with respect to said aligned end portions to thereby provide clearance for the swinging movement of the eyes about the mentioned vertical axes.

11. An eye set comprising a pair of semi-spherical eye shells spaced apart, supporting means for said eye shells providing pivotal mounting by which the eye shells are adapted to oscillate upon both vertical and horizontal axes, gravity means for so oscillating said eyes, each of said eyes comprising a pair of separate semispherical shells nested together and adjustably movable with respect to each other, and the part of said supporting means which provides pivotal mounting upon the vertical axis in each eye having portions providing also pivotal connection between the shells of the respective eyes.

12. In an eye set, a pair of eyes spaced apart, supporting means for the eyes by which the eyes are pivotally mounted to swing in opposite directions upon vertical axes transverse to a straight line between said eyes, gravity means for so swinging said eyes, each of said eyes comprising a pair of separate semispherical shells nested together and adjustably movable with respect to each other, and means interengaging between the supporting means and the inner shell of each eye for limiting the gravity movement of the eye in said opposite directions.

45 13. In an eye set, a pair of eyes spaced apart, supporting means for the eyes by which the eyes are pivotally mounted to swing upon vertical axes transverse to a straight line between said eyes, gravity means for so swinging said eyes, each of said eyes comprising a pair of separate semi-spherical shells nested together having aligned bearing openings therethrough, means interengaging between the supporting means and the inner shell of each eye for limiting the gravity movement of the eye, and the pivotal connection between the respective eyes and their supporting means including pivot parts of the supporting means engaging within said aligned openings of the two shells serving thereby to positively connect said shells together.

65 14. In an eye set, the combination of a pair of eye shells spaced apart, a rotatable cross rod extending between said eye shells, con-

necting members by which said eye shells are connected to the opposite end portions of the cross rod to rotate therewith, the end portions of the cross rod extending in axial alignment with each other and intersecting the spherical centres of the eye shells, the connecting members and the end portions of the cross rod being constructed to provide independent manual adjustment of the respective eye shells about the end portions of the cross rod, a support for the cross rod engaging said aligned end portions to rotatably support the cross rod, gravity acting means to rotate the cross rod and eye shells, and the portion of the cross rod intermediate the aligned end portions thereof being off-set and provided with stops to limit rotary movement of the cross rod and eyes.

In testimony whereof we affix our signatures.
